UNITED STATES PATENT OFFICE.

GUSTAV KUSS, OF SOUTH BEND, INDIANA.

DESIGN FOR A GAME-BOARD.

SPECIFICATION forming part of Design No. 32,837, dated June 12, 1900.

Application filed May 5, 1900, Serial No. 15,662. Term of patent 14 years.

To all whom it may concern:

Be it known that I, GUSTAV KUSS, a citizen of the United States, residing at South Bend, in the county of St. Joseph and State of Indiana, have invented a certain new and original Design for Game-Boards; and I do hereby declare that the following is a full, clear, and exact description of the invention, such as will enable others skilled in the art to which it applies to make and use the same.

My design relates to the new and original shape or configuration of the article.

The leading or essential feature consists of the unitary design for a game-board made the subject of the illustration, in which I have shown my invention in plan view, comprising the base or body portion, the rim or border thereon, the upright guides mounted upon the face of the playing-surface of the board, and the cross-lines having the marked center located at the center of the playing-surface of the board.

As shown in the drawing, my game-board consists of the square body portion A, provided with an upwardly-extending rim or border B. This rim or border B is provided with thickened corner portions and is curved on its inner side so as to form a "rounded corner" a. At the center portion of two sides of the said square body portion A the border

or rim B is curved so as to form the inwardly-projecting points b.

Upon the surface of the board A and arranged in close proximity to the border or rim B are two upright guides C, each of which is provided with the curved end portions c, which are so arranged with relation to the rim or border B that a channel or guideway is left therebetween. The four ends c are arranged in pairs at each end of the game-board, and between each of the said pair of ends is left an opening leading to the center of the board.

At the exact center of the board is a mark or circle, and diverging therefrom are eight lines D, the ends of which are each provided with a mark or circle similar to the mark or circle at the center of the board.

Having thus described the nature of my invention, what I claim as new, and desire to secure by Letters Patent of the United States, is—

The design for a game-board, substantially as herein shown and described.

In testimony whereof I have hereunto signed my name in the presence of two subscribing witnesses.

GUSTAV KUSS.
